UNITED STATES PATENT OFFICE.

VERNON GARNER, OF BOSTON, MASSACHUSETTS, ASSIGNOR TO UNITED PRINTING MACHINERY COMPANY, OF BOSTON, MASSACHUSETTS, A CORPORATION OF MAINE.

MULTIPLE-SHEET DETECTOR FOR PAPER-FEEDING.

1,142,247.

Specification of Letters Patent.

Patented June 8, 1915.

Original application filed November 16, 1912, Serial No. 731,862. Divided and this application filed March 5, 1914. Serial No. 822,637.

To all whom it may concern:

Be it known that I, VERNON GARNER, a citizen of the United States, and resident of Boston, in the county of Suffolk and State of Massachusetts, have invented certain new and useful Improvements in Multiple-Sheet Detectors for Paper-Feeding, of which the following is a specification.

This invention relates to paper-feeding machinery such as that used for feeding paper sheets one by one to a printing press or other paper-handling machine, and is a division of my copending application filed November 16, 1912, Serial Number 731,862.

The invention is embodied in mechanism for arresting the travel of the sheets toward the printing press or other paper-handling machine when two or more sheets are fed one upon another.

Of the accompanying drawings, which illustrate the invention: Figure 1 represents a side elevation of the sheet-detecting mechanism in coöperative relation to paper-feeding means. Fig. 2 represents a similar elevation, on a larger scale, of the essential elements of the detector. Fig. 3 is a view similar to Fig. 2, showing the parts in sheet-arresting position.

The same reference characters indicate the same parts wherever they occur.

Fig. 1 includes an endless band 10 which travels over rolls 11 and 12, in the direction indicated by an arrow, to carry the sheets to a printing press or other machine. It is customary in paper-feeding machinery to arrange a plurality of such bands side by side upon the rolls 11 and 12, which are as long as the width of the sheets.

The multiple-sheet detector is arranged between the rolls 11 and 12 and acts when two or more sheets are conveyed one upon another by the bands 10, the detector being adapted to stop such sheets as may be disposed one upon another while traveling on the bands. An abutment for arresting the sheets is indicated at 15, and is affixed to a rockshaft 16. In practice, two or more of these abutments will be provided and will be arranged in alinement so as to act in unison.

When the rockshaft is turned, the abutments are moved to and from the path of the sheets between the bands 10. A finger 17 affixed to the rockshaft is adapted to rest upon the upper end of a trip or releasing member 18.

This member is mounted upon a fulcrum 19, and when engaged with the finger 17 as shown by Figs. 1 and 2 it supports the abutments 15 above the path of the sheets. A compression spring 20 is connected by suitable means with the rockshaft for the purpose of throwing the abutments downwardly across the path of the sheets when the releasing member 18 is disengaged from the finger 17.

The releasing member is automatically operated by the sheets when two or more are conveyed one upon another. For this purpose the device is provided with a gage, which comprises coöperative caliper members 21 and 22. These caliper members are disposed respectively above and below the path of the sheet, and one of them is adjustable toward and from the other so that the space between them may be determined to permit a single sheet to pass without tripping the abutments 15. The caliper member 21 is a driven roll, and it is driven by suitable gearing whereby the sheet-engaging portion is caused to travel in the same direction as the sheets. The details of the gearing are not of special importance, and for this reason need not be described. The upper caliper member 22 is mounted upon a pivot pin 23. The sheet-engaging surface of the member 22 is segmental, and the operating movement of the member is a swinging movement about the pivot 23. This movement is transmitted to the releasing member 18 by a link 24, arm 25, rockshaft 26, arm 27, and link 28. The member 22 is so weighted that it normally hangs in the position shown by Figs. 1 and 2, with the releasing member 18 in position to support the abutments 15.

The pivot 23 is mounted in an adjustable support 29, and the support is arranged upon a pivot 30, the pivot 23 being movable toward and from the path of the sheets in consequence of this arrangement. An adjusting screw 31 is arranged to act upon the support 29 to determine the desired space between the caliper members. The adjusting screw is arranged in a fixture 32.

In practice, the caliper members will be adjusted to provide a space slightly more than the thickness of one of the sheets which are to be fed, but less than the thickness of two sheets. When the caliper members

are so spaced, single sheets may pass between them without causing any movement of the member 22; but when two sheets, one upon another, pass between the caliper means 5 members, their combined thickness causes the upper sheet to be pressed against the member 22 with sufficient pressure to impart movement to the member 22 about its pivot. The actuating element for tripping the abutments is the driven roll 21, and the sheets act to transmit rotary motion from the roll to the upper caliper member 22. The force required to disengage the releasing member 18 from the finger 17 is very slight, 15 and the mechanism for causing the release of the abutments is sensitive in action. When the abutments are thrown into the path of the sheets, the progress of the sheets is arrested, and when the sheets so arrested 20 are removed from the detecting mechanism the latter may be restored to its initial position by lifting the abutments until the finger 17 is above the end of the releasing member. As previously stated, the caliper means 25 member 22 is so weighted that it normally seeks the position shown by Figs. 1 and 2, and for this reason the releasing member 18 will be automatically placed in abutment-supporting position when the abutments are 30 raised as just stated.

I claim:

1. In a sheet feeder, the combination with an endless band conveyer, of caliper means arranged to be operated by two or

more sheets, one upon another, upon said 35 conveyer, and means arranged to stop the sheets between the ends of said conveyer, in consequence of operation of said caliper means.

2. In a sheet-feeder, movable means for 40 supporting and conveying sheets one at a time, caliper means adapted to be operated by a plurality of sheets one upon another in transit, yielding means adapted normally to stand in the path of the sheets beyond 45 said caliper means, and restraining means connected to said caliper means for holding said yielding means out of the path of the sheets, said restraining means being adapted to release said yielding means 50 in consequence of operation of said caliper means.

3. In a sheet feeder, the combination with an endless band conveyer, of caliper means 55 arranged to be operated by two or more sheets, one upon another, upon said conveyer, and an abutment arranged to be moved into the path of the sheets in front of the sheets and between the ends of said conveyer, in consequence of operation of said 60 caliper means.

In testimony whereof I have affixed my signature, in presence of two witnesses.

VERNON GARNER.
